(74) *Attorney, Agent, or Firm* — Avyno Law P.C.

(57) **CLAIM**

I claim the ornamental design for a target game, as shown and described.

DESCRIPTION

FIG. 1 is a top front perspective view of the target game of the present invention.

FIG. 2 is a top rear perspective view of the target game of FIG. 1.

FIG. 3 is a bottom rear perspective view of the target game of FIG. 1.

FIG. 4 is a front elevation view of the target game of FIG. 1.

FIG. 5 is a rear elevation view of the target game of FIG. 1.

FIG. 6 is a side elevation view of the right side of the target game of FIG. 1.

FIG. 7 is a side elevation view of the left side of the target game of FIG. 1.

FIG. 8 is a top plan view of the target game of FIG. 1; and, FIG. 9 is a bottom plan view of the target game of FIG. 1.

In the drawings, the broken lines depict portions of the target game that form no part of the claimed design.

1 Claim, 8 Drawing Sheets
